TYPEWRITER ATTACHMENT

Willibald Weniger, Corvallis, Oreg.

Application July 14, 1932, Serial No. 622,415

7 Claims. (Cl. 197—180)

My invention relates to typewriters and has for an object the provision of a simple and reliable means whereby more and different characters than those controlled by the typewriter keys are 5 made available.

In scientific work characters other than those found on the standard keyboard are nearly always used. For example, letters of the Greek alphabet and mathematical symbols are essential for the 10 writing of formulae and equations. Heretofore special typewriters have been supplied for such special uses but their field of usefulness is limited. Furthermore skilled typists use the touch method of operating the standard keyboard and 15 as a rule refuse to use a special machine.

In carrying out my invention in one form thereof, I provide a support which is secured to the typewriter in such a manner that auxiliary type bars may be placed on the support in operative 20 relation with respect to the platen of the typewriter. Each auxiliary type bar is provided with a projection by means of which the bar may be driven against the platen by one of the regular type bars.

25 For a more complete understanding of my invention reference should now be had to the drawing in which Figure 1 is an enlarged perspective view of my invention as applied to a typewriter; Figure 2 is a front elevation of Figure 1, while Figure 3 shows a side elevation of Figure 2.

Referring now to the drawing, I have shown my invention in one form as applied to a typewriter of which a type guide 10 is shown secured to the typewriter frame 11. A support 12 for an 35 auxiliary type bar, for example the bar 13, is mounted from the ends 14 and 15 of the type guide 10. As shown, the support 12 is slotted as indicated by the reference numeral 17 so that the type guide ends 14 and 15 cooperate in securing 40 the support in the position shown. The auxiliary bar 13 is rigidly secured at its upper end to a rod 19. This rod 19, nesting in the grooves 20 of the support 12, serves to suspend the bar 13 for movement against the ribbon 22 and the platen 23.

45 It will be understood that there are provided as many auxiliary type bars as may be desired and at the lower end of each bar there are provided special reference characters, as indicated at 24.

A projection 26 is formed on the opposite side 50 of the type bar 13 and is of such a dimension and is so placed that when the bar 13 is actuated by any type bar of the typewriter, for example the type bar 30, the projection 26 will engage the type bar between its printing surfaces. The projection is designed with reference to the majority

of the type bars on the typewriter. For example, on the standard keyboard any type bar may be used to actuate the auxiliary bar except the one having the underscore. If the underscore type bar is used the underscore would strike the projection to the damage of the underscore type. 60

In applying my invention to a typewriter, the support 12 is attached to the typewriter by means of the slots which engage the ends 14 and 15 of the type guide. The typewriter is then used in 65 the ordinary way until a special character is desired. The proper bar, for example 13, is then selected and placed in position on the bearings 20 of the support. Any key (except the underscore) is depressed in the ordinary manner causing its 70 type bar to strike the projection 26. The auxiliary type bar 13 is thereby caused to strike the ribbon 22 and the platen 23 and thus print on a piece of paper in contact with platen 23 the particular character needed. 75

It will be observed that each auxiliary type bar, as illustrated by the bar 13, is provided with two special characters and a particular one is selected by the operation of the shift key in the usual manner. The special characters strike the platen 80 with sufficient force so that carbon copies and stencils are easily made. As soon as the special character, or characters, have been printed the auxiliary key is removed from the support 12 and the typewriter is then used in the usual manner 85 until the next special character is needed.

I have found that less time is required in printing the special characters by means of my invention than is required in inserting the necessary characters by hand and that the beauty of the 90 typed copy is greatly enhanced.

Now that the principles of my invention have been explained it will be obvious to those skilled in the art that the type of support for the auxiliary bars may be radically altered for easy mounting 95 on commercial typewriters, while changes may be made in details, dimensions and arrangements and certain features used without other features without departing from the spirit of this invention. Reference is, therefore, to be had to the 100 claims hereto appended for a definition of the limits of said invention.

What I claim as new and desire to secure by Letters Patent of the United States, is:

1. An attachment by means of which additional characters are made available on a typewriter comprising, an auxiliary type bar, and removable mounting means for mounting said auxiliary bar in such manner that it can be operated by any selected one of the type bars on 105 110

the typewriter into engagement with the platen of said typewriter while preventing the engagement of said selected type bar with said platen.

2. An attachment for typewriters of the type having outwardly extending projections on the type guide, combining supporting means having slotted ends for engagement with said projections, an auxiliary type bar, and means on said supporting means for pivotally mounting said type bar in printing position between said projections of said type guide.

3. An attachment for a typewriter provided with a platen, type bars, means for operating said type bars, and a type guide, comprising a supporting member, means for mounting said member from said type guide, and an auxiliary type bar provided with reference characters on one face and a projection on the opposite face, said supporting member providing a pivotal support

10 15 20 25 30 35 40

for suspending from a point above said type guide said auxiliary type bar with said reference characters between said type guide, said projection serving to receive a character imprinting blow from one of said type bars.

4. An attachment for a typewriter having a type guide, a platen, and type bars, comprising an auxiliary type bar provided with reference characters on one face thereof and a projection on the opposite face thereof, a support provided 30 35 40

with grooves located above said type guide, a pin secured to said type bar in spaced relation with said reference characters and arranged to rest within said grooves for pivotally mounting from a point above said type guide said auxiliary bar so that said projection receives an imprinting blow from one of the typewriter type bars to actuate said auxiliary bar into engagement with said platen.

5. An attachment for typewriters of the type 40 having outwardly extending projections on the

type guide, comprising supporting means having slotted ends for engagement with said projections, an auxiliary type bar provided with reference characters on one face and an operating projection on the opposite face, and means on said supporting means for pivotally mounting said type bar in printing position between said projections of said type guide, said operating projection of said type bar serving to receive an imprinting blow from one of the type bars of said typewriter.

6. An attachment for typewriters of the type having outwardly extending projections on the type guide, comprising a supporting member having slotted ends for engagement with said projections, an auxiliary type bar provided with reference characters on one face and an operating projection on the opposite face, said supporting means being provided with supporting grooves for pivotally mounting said type bar in operating position between said projections of said type guide so that any one of the type bars of said typewriter can be operated into engagement with said operating projection to actuate said auxiliary bar into printing engagement with said platen.

7. An attachment by means of which additional characters are made available on a typewriter provided with a platen and type bars having reference characters thereon, comprising, an auxiliary type bar provided with reference characters 105 on one face thereof and a projection on the opposite face thereof, removable mounting means for mounting said auxiliary type bar in such manner that it can be operated by any one of the type bars on the typewriter into engagement with the platen 110 of said typewriter, said projection being positioned so that it is engaged by the selected one of said typewriter type bars intermediate the reference characters on said typewriter type bars.
